United States Patent Office

Des. 230,780

Patented Mar. 12, 1974

230,780

BICYCLE STAND

Daniel C. Myers, 6209 Iris Way,
Arvada, Colo. 80002

Filed Aug. 30, 1972, Ser. No. 285,088

Term of patent 14 years

Int. Cl. D12—11

U.S. Cl. D90—18

FIG. 1

FIG. 2

FIG. 3

FIG. 1 is a side elevational view of a bicycle stand embodying my new design.

FIG. 2 is a top plan view thereof with the chains being omitted for ease of illustration.

FIG. 3 is a perspective view of one segment of the bicycle stand shown in FIG. 1.

FIG. 4 is a front elevational view thereof.

FIG. 5 is a rear elevational view thereof.

FIG. 6 is a right side elevational view thereof.

FIG. 7 is a left side elevational view thereof.

I claim:

The ornamental design for a bicycle stand, as shown and described.
